(57) **CLAIM**

The ornamental design for a shearing guide for carpet trimmer, as shown and described.

DESCRIPTION

FIG. 1 is a front, right and top perspective view of a shearing guide for carpet trimmer, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the shearing guide for carpet trimmer when in use.

The broken lines shown in FIGS. 1-8 depict portions of the shearing guide for carpet trimmer that form no part of the claimed design. In FIG. 9, the broken lines depict environmental structure that form no part of the claimed design.
